UNITED STATES PATENT OFFICE.

JAMES A. BISHOP, OF CHICAGO, ILLINOIS.

COKE-OVEN CONSTRUCTION.

Application filed September 8, 1919. Serial No. 322,515.

To all whom it may concern:

Be it known that I, JAMES A. BISHOP, a citizen of the United States, residing at Chicago, in the county of Cook and State 5 of Illinois, have invented certain new and useful Improvements in Coke-Oven Constructions, of which the following is a specification.

The present invention has to do with certain improvements in coke oven constructions. Certain features of the invention have reference to coke oven constructions so arranged that the necessary coking period within the coke oven proper may be shortened, thereby increasing the output or capacity of the installation. Another object in this connection is to make it possible to so shorten the coking period while at the same time ensuring a practically complete 20 recovery of the by-products in good form and without damage to the coking operation.

I will state at this point that the coke produced in the so-called Bee-Hive type of oven derives many of its desirable qualities from the fact that the coking period is extended over a considerable length of time, so that an annealing action or process takes place which beneficially alters or modifies the coke structures. The Bee-Hive oven, 30 however, presents the objectionable features that the by-products are lost or wasted, and also the coking period is relatively long, so that the yearly output of a given installation is relatively small.

One of the objects of the present invention is to provide, in combination, with a coke oven of suitable construction, a chamber or compartment within which the hot coke delivered from the main coking chamber is retained for a certain length of time out of contact with the air, so that the annealing or similar process may continue without oxidation even after the coke has been discharged or delivered from the coking chamber or retort.

Other objects of the invention are to provide an improved feeding mechanism and construction for continuously delivering the raw coal into the coking chamber, and for 50 moving the coking material through said chambers to the point of discharge either to the atmosphere or to an annealing chamber such as I have previously mentioned.

Another object of the invention is to provide means for the introduction of steam,

air or other gas into the body of the coking material under control, so that the nature and quality of the completed coke may be accordingly altered or controlled.

Other objects of the invention are to provide a type of coke oven construction which shall be very well adapted for the treatment of oil shales for the distillation of oil therefrom. When the apparatus is used for the distillation of such material, it performs functions similar, in many respects, to those of an ordinary coke oven, but the operating conditions are such that the apparatus should, in some respects, be modified in order to distill the oil shales to the best advantage. I may state in this connection that in the distilling of such materials use is ordinarily made of a lower temperature than is used in ordinary coking operations, and, therefore, one of the features of the invention has to do with the provision of arrangements whereby the temperature may be modified within the coking chamber, while at the same time beneficially affecting the vapors distilled off from the shales.

Other objects and uses of the invention will appear from a detailed description of the same which consists in the features of construction and combinations of parts hereinafter described and claimed.

In the drawings:

Figure 1 shows a vertical section through the central portion of the typical coke oven embodying certain features of the present invention; and

Fig. 2 shows a vertical section through an annealing chamber or the like which may be used in conjunction with a coke oven structure for the annealing or similar treatment previously mentioned herein; and

Fig. 3 shows diagrammatically an arrangement in which two ovens such as that shown in Fig. 1 can deliver material to a common "annealing" chamber such as that shown in Fig. 2.

I will state in the first place that for the practice of the feature involving the subsequent or annealing treatment, any suitable type of retort oven may be used, but the oven construction which I will now describe in detail is very well adapted for this particular purpose. This particular oven includes a circular chamber 3 having the floor 4 and a dome-shaped roof 5. Within the chamber is rotatably mounted a vertical pivotal mem-

ber 6 extending from which are a plurality of radial arms 7 and 8. On each of these arms is mounted one or more shovels or the like 9 set at an inclination or angle, so that, upon rotating the entire mechanism, coal, shales, or other material introduced into the central portion of the chamber will be gradually worked or forced in a radial direction towards a discharge or exit point or opening 10.

The arms 7 and 8 are preferably hollow, and in like manner the pivotal member 6 has a vertical passage 11 in its lower portion through which cooling water may be circulated into the arms. One or more diagonal stays or the like 12 and 13 have their outer ends in communication with the end portions of the arms, and have their inner ends in communication with a vertical passage 14. Consequently the water circulated through the radial arms may return inwardly to the diagonal stay members and be discharged upwardly out of the arms. The pivotal member communicates with a stuffing box 15 at its lower end, and with a stuffing box 16 at its upper end, so that the water may be initially introduced through the pipe 17, and finally discharged through the pipe 18.

Constructions of this general type are shown and described in Letters Patent of the United States No. 1,166,175 issued to me under date December 28, 1915.

In the present construction the coal, shale or other material is introduced in the first instance into a hopper or the like 19 from which it is moved by a conveyor 20 to a central hopper 21 contained within a gas chamber or seal 22 above the upper central portion of the coking chamber. One or more chutes 23 extend downwardly in spiral fashion from the hopper 21 to a delivery spout 24 through which the raw material is delivered into the central portion of the floor 4. The hopper 21 with the spiral chute 23 and spout 24 rotate with the stirring or transferring mechanism, so that the coal or other material is uniformly delivered around the central portion of the floor. The distillate gases pass upwardly through an annular opening 25 into the chamber 22, and a discharge connection 26 leads from the chamber 22 to a suitable gas receiving mechanism.

One or more of the shovels may be hollow and provided with perforations or openings 27. A steam pipe 28 extends down through the interior of the passage 14 and delivers steam into a chamber 29. From this chamber the steam passes on down and is delivered to the interior portions of the shovels 27 through the connections 30 and 31. The heat of the coking chamber serves to superheat the steam before it reaches the shovels. It will be observed that by this construction the steam may be delivered into the body of the coal or other material undergoing treat-

ment so as to correspondingly modify or alter the distillate gases given off, and also the structure of the residuum.

The rotating spindle or shaft may be driven by a gear 32 contained within a chamber 33 in the lower central portion of the foundation. A thrust bearing 34 serves to carry the load of the rotating mechanism at a point where the temperature is normal, so that the wearing qualities of the thrust bearing will not be interfered with.

In order to provide a seal against the loss of distillate gases, and in order to prevent the entrance of dust into the bearing parts, a sleeve 35 is provided surrounding the hollow shaft member 11, said sleeve having a flange 36 which is embodied in the foundation structure, and a stuffing box 37 closes the lower end of the sleeve in close engagement with the rotating shaft so as to prevent the loss of gas.

It was previously explained that one of the objects of the invention is to provide for further treatment or annealing of the coke when the apparatus is to be used for the manufacture of coke. For this purpose, I have provided a chamber 38 shown in perspective in Fig. 2, which chamber has one or more entrance openings 39 and 40, through which the coked material may be introduced into it from one or more adjacent coke ovens. For example, two ovens such as that above described may deliver their product into this chamber through the openings 39 and 40. When the annealing chamber is used in conjunction with two coke ovens, it will be understood that the annealing chamber may perform double duty, and in such case the annealing time may be greater than the coking time without interfering with the continuous or most economical operation of either the oven or annealing chamber.

The annealing chamber is provided with a slanting floor 41 which leads towards a breaker and conveying mechanism by means of which the annealed coke may be delivered from the chamber under seal. For this purpose a trough 42 is provided adjacent to the lowest portion of the chamber, within said trough being a shaft 43 carrying a screw or other conveyor 44. The trough may be filled with water for the purpose of quenching the coke and for establishing a water seal.

Above this conveyor is mounted a breaker shaft 45 on which are located a number of breaker points 46 which are set at different angular positions on the shaft, so that they come into operation in succession. In this way the load on the shaft 45 is made practically uniform and the operation of the machine is correspondingly improved. As the coke works down towards the breaker, portions are broken off from its lower edge and delivered into the trough where they are quenched and then removed by the conveyor.

In order to prevent "bridging" of the coke, I have provided a pair of rock shafts 47 and 48 which carry the lugs 49 working within slots 50 in one of the walls of the 5 chamber. By periodically rocking these shafts, the coke will be forced down against the breaker and the formation of bridges will be prevented.

While I have herein shown and described 10 only certain embodiments of the features of the present invention, it is understood that I do not limit myself to the embodiment except as I may do so in the claims.

I claim:

15 1. Coking apparatus comprising in combination an annealing chamber having a downwardly slanting floor leading to a breaker pit, a rotary breaker within said pit, means for removing broken material from said pit 20 under gas seal, together with a continuous coke oven located at each side of said annealing chamber, a delivery passage from each of said coking chambers to the annealing chamber for the delivery of coke onto said floor, 25 and means within each of said coking cham-

bers for delivering coked material through its passage into the annealing chamber, substantially as described.

2. Coking apparatus comprising in combination a substantially air tight annealing 30 chamber having a downwardly slanting floor and a pair of oppositely disposed openings for delivering coked material onto said floor, together with a continuous process coke oven at each side of the annealing chamber in position for the continuous delivery of coked 35 material through its opening onto said floor, substantially as described.

3. Coking apparatus comprising in combination a substantially air tight annealing 40 chamber having a downwardly slanting floor and a pair of oppositely disposed openings for delivering material onto said floor, together with a coke oven at each side of the annealing chamber adapted to deliver coked 45 material through the corresponding opening into the annealing chamber under air seal, substantially as described.

JAMES A. BISHOP.
